METHOD FOR ALLEVIATING GASTRIC MUCOSAL BLEEDING

BACKGROUND OF THE INVENTION

It is well documented that carboxylic acids, such as acetic, propionic, butyric, and, most significantly, acetylsalicylic acid (aspirin), in a highly acidic pH gastric environment, can diffuse through the gastric mucosa, producing injury to the mucosal barrier. Once the integrity of the mucosal barrier has been damaged, back diffusion of acid results, and this is accompanied by gastric bleeding.

It has now been discovered that gastric bleeding can be alleviated by administering glucagon to a subject experiencing such bleeding. Furthermore, gastric bleeding can be prevented or substantially diminished by administering glucagon to a subject who can be reasonably expected to experience gastric bleeding.

Structurally, glucagon is a single polypeptide chain of 29 amino acids. The amino acid sequence of glucagon was established by Bromer et al., J. Am. Chem. Soc., 79, 2807 (1957). Glucagon exhibits a hyperglycemic effect and, thus, has long been recognized as useful in treating hypoglycemia. However, it has never been considered that glucagon would be active in alleviating gastric bleeding. It is to the use of glucagon in treatment of gastric bleeding that this invention is directed.

DETAILED DESCRIPTION OF THE INVENTION

Broadly, this invention is directed to a method for alleviating gastric mucosal bleeding which comprises parenterally administering to a mammal a therapeutically effective amount of glucagon.

Therefore, the core of this invention resides in the discovery that glucagon is effective in alleviating, terminating, or preventing gastric bleeding. The glucagon is administered to a warm-blooded animal who is experiencing gastric bleeding, or it is administered to one who might reasonably be expected to experience gastric bleeding.

The glucagon dosage level is an amount sufficient to diminish or to terminate gastric bleeding. Generally, the dosage level will be within the range of from about 1.0 μ g. to about 200 μ g. per kg. body weight of the recipient, and, preferably, from about 25 μ g. to about 150 μ g. per kg. body weight, and, most preferably, from about 25 μ g. to about 100 μ g. per kg. body weight. Furthermore, the total dosage can be single or cumulative. By "cumulative" is meant a dosage measured in terms of multiple individual smaller doses, with each such individual dose being administered prior to completion of the recipient's response to the previous dose.

Any of the generally employed methods for administering glucagon can be employed. These include all of the usual parenteral routes, for example, intravenous, intraperitoneal, subcutaneous and intramuscular. Preferably, however, the glucagon is administered subcutaneously (s.c.).

Glucagon is active in preventing or retarding gastric bleeding when administered to a mammal which is susceptible to such malady or in alleviating or terminating gastric bleeding when administered to one which exhibits such bleeding. The cause of the gastric bleeding is not crucial to the effectiveness of the glucagon in achieving alleviation. Preferably, however, this invention

is directed to treatment of gastric bleeding when such bleeding has been initiated or is reasonably expected to occur from ingestion of an ulcerogenic anti-inflammatory agent. Typical such agents include acetylsalicylic acid (aspirin), indomethacin, phenylbutazone, and the like. Most typically, the gastric bleeding will result from ingestion of acetylsalicylic acid.

The recipient of the glucagon can be any mammal, human or non-human, who is experiencing or can reasonably be expected to experience gastric bleeding.

The alleviation or prevention of gastric mucosal bleeding by administration of glucagon is illustrated by the following experimental procedure and data. The particular procedure, however, is not intended to be limiting upon the broad scope of the discovery of this invention.

EXAMPLE

Four female dogs, weighing 22-25 kg. each, were 20 surgically altered to provide a vagally innervated gastric fistula as well as a denervated fundic (Heidenhain) pouch. The dogs were so prepared at least one month prior to any use experimentally. No dog was used experimentally more than once per each 14 day period.

25 The experimental procedure was commenced by fasting each dog for 18 hours, although each was permitted to have free access to water. Under these basal conditions there was no measurable gastric acid secretion. The pouch then was washed thoroughly with 0.1 N

30 HCl. Additional 0.1 N HCl (25 ml.) then was instilled (infused) into the pouch and was maintained there for 30 minutes. The pouch then was drained, and the HCl was saved for analysis. Immediately, 25 ml. of fresh 0.1 N HCl was instilled in the pouch and maintained there

35 for a 30 minute period. This process was repeated each 30 minutes for a total of 6 hours. Thus, a total of 12 portions (designated herein as Periods 1-12) of 0.1 N HCl were instilled into and recovered from the pouch. All instillates (infusates) except those of Periods 4, 5, 40 and 6 were identical in composition. To those of Periods 4, 5, and 6 were added 5 mg/ml. (27.8 mmoles) of acetylsalicylic acid (aspirin).

Blood flow to the gastric mucosa of each of the dogs was measured by clearance of plasma aminopyrine into 45 the HCl instillate. Thus, aminopyrine was administered to each of the dogs. It was maintained at a steady level in the plasma of the dog by continuous infusion intravenously at a rate of 5 mg/kg.-hr. following an initial dose of 20 mg./kg. administered prior to commencement of

50 addition of HCl to the Heidenhain pouch. The presence and amount of aminopyrine in the instillate was determined by extracting it from the instillate using a procedure described by Jacobson et al., "Blood Flow and Secretion in the Stomach," *Gastroenterology*, 52, 55 (1967) pp. 414-420; and Jacobson et al., "Gastric Secretion in Relation to Mucosal Blood Flow studied by a Clearance Technic," *Jour. Clin. Invest.*, 45, (1966) pp. 1-13, with the minor modification described in Lin et al., "Effect of Glucagon on Pentagastric-induced Gastric Acid Secretion and Mucosal Blood Flow in the Dog," *Gastroenterology*, 61 (1971) pp. 328-331. Concentration of aminopyrine in the extract was then determined by its absorption at 260 m μ measured spectrophotometrically.

60 65 Each of the four dogs also was administered Cr⁵¹ by slow infusion intravenously of Cr⁵¹ Cl₃ (25 μ Ci/kg) over a 3 hour period on the day prior to testing. Plasma transferrin thereby was tagged with Cr⁵¹, and this pro-

vided a ready measure of plasma transferrin and, in turn, a measure of any loss of plasma from the blood to the lumen. The amount of Cr^{51} in the blood and the amount in the infusate were monitored using a γ -spectrometer, and any loss of plasma protein thereby was calculated.

The preceding description constitutes a definition of the control sequence. All four dogs were treated as aforescribed, and therefrom control data were generated. However, 14 days prior to carrying out the control sequence, the same four dogs were treated as aforescribed with the exception that each additionally received glucagon. The glucagon was administered subcutaneously (s.c.) in two separate doses of 50 $\mu\text{g}/\text{kg}$. each. The doses were administered at the outset of Periods 5 and 7, that is, simultaneously with administration of the second infusate containing acetylsalicylic acid and upon removal of the third (last) infusate containing acetylsalicylic acid.

In addition to the aforementioned analytical techniques, the infusate withdrawn from each of the four dogs after each of the 12 periods was subjected to further analysis.

The extent of gastric bleeding was determined by measuring the amount of hemoglobin present in the infusate relative to the hemoglobin concentration in the blood of the respective dog. Hemoglobin was measured as acid hematin in accordance with Cohen et al., "The Colorimetric Determination of Hemoglobin", *Jour. Biol. Chem.*, 39, (1919) pp. 489-496.

Acidity of the recovered infusate was determined by titration to pH 7 with 0.05 N NaOH, and the concentration of the sodium (Na^+), potassium (K^+), calcium (Ca^{++}), and magnesium (Mg^{++}) ions were measured by atomic absorption.

Results from the testing of the four dogs under these conditions are depicted herein by means of the graphs provided.

FIG. 1 depicts the effect of aspirin and aspirin-glucagon on the volume of recovered instillate from the Heidenhain pouch of the four dogs. The abscissa represents the twelve periods of thirty minutes each, and the ordinate presents the volume in milliliters of instillate recovered.

FIG. 2 depicts the effect of aspirin and aspirin-glucagon on the hydrogen ion (H^+) concentration in the recovered instillate from the Heidenhain pouches of four dogs. Values represent the means $\pm$ s.e.m. The abscissa represents the 12 periods of 30 minutes each, and the ordinate presents the hydrogen ion concentration in milliequivalents (meq) per liter (1).

FIG. 3 depicts the effect of aspirin and aspirin-glucagon on the clearance of plasma aminopyrine from the Heidenhain pouches of the four dogs. Values represent the means $\pm$ s.e.m. The abscissa represents the 12 periods of thirty minutes each, and the ordinate presents aminopyrine clearance in milliliters per minute.

FIG. 4 depicts the effect of aspirin and aspirin-glucagon on hemorrhage into the instillate of the Heidenhain pouches of the four dogs. The abscissa represents the 12 periods of 30 minutes each, and the ordinate presents total blood in milliliters.

FIG. 5 depicts the effect of aspirin and aspirin-glucagon on the loss of plasma transferrin- Cr^{51} into the instillate of the Heidenhain pouches of the four dogs. Values represent the means $\pm$ s.e.m. The abscissa represents the 12 periods of 30 minutes each, and the ordinate

presents microliters ($\mu\text{l}.$) of plasma per milliliter (ml.) of instillate.

FIG. 6 depicts the effect of aspirin and aspirin-glucagon on the net efflux (concentration) of Na^+ , K^+ , Ca^{++} , and Mg^{++} in the instillate of the Heidenhain pouches of the four dogs. Values represent the means $\pm$ s.e.m. The abscissa represents the 12 periods of 30 minutes each, and the ordinate presents the cation concentrations in milliequivalents per liter (meq/l) of recovered instillate.

As is apparent from FIG. 1, during the three control periods, 24.2 to 25 ml. of acid instillate were collected from the pouch at 30 minute intervals. There was no significant difference in volume of instillate recovered during the control periods of the aspirin test when compared with those of the aspirin-glucagon test.

After the assault with a combination of 0.1 N HCl and aspirin for three 30 minute periods, a gradual but significant increase in volume of recovered instillate resulted. This increase continued for at least 3 hours after cessation of aspirin administration, and the peak increase was 7.3 ml. above control. Administration of glucagon subcutaneously (s.c.) in two doses of 50 $\mu\text{g}/\text{kg}$, each and 60 minutes apart, significantly reduced the volume of instillate recovered during Periods 6-8 when compared to the volume recovered by administration of aspirin alone. The volume reduction amounted to a total of 17.2 ml.

The hydrogen ion (H^+) concentration in the recovered instillate from both series of tests remained essentially steady at 95 meq/l before administration of aspirin (FIG. 2). A significant decrease of H^+ concentration was seen 60 minutes after assault with HCl and aspirin. The reduction in acid concentration persisted for about three hours after termination of aspirin administration. The difference in acid concentration between administration of aspirin alone and administration of the glucagon-aspirin combination was not significant.

Gastric mucosal blood flow is indicated by clearance of plasma aminopyrine (FIG. 3). Clearance of plasma aminopyrine was significantly increased by administration of aspirin, and this increase persisted for about three hours after termination of aspirin administration. The administration of glucagon significantly reduced the clearance of aminopyrine and, thus, of the mucosal blood flow in Periods 6-8. The extent of reduction indicated a mucosal blood flow reduced to an amount even below that obtained prior to aspirin administration.

Mucosal hemorrhaging caused by aspirin was significantly reduced throughout the test by administration of glucagon (FIG. 4). The mean of total blood loss during a 4.5 hour period was 12.3 ml. in the aspirin controls, whereas administration of glucagon reduced total blood loss to only 6.8 ml.

The concentration of plasma protein in the lumen, calculated by measuring Cr^{51} transferrin in the instillate and in the plasma, was, in the aspirin controls, 46.4 $\mu\text{l}/\text{ml}$. over a 4.5 hour period. Administration of glucagon reduced this to 19.1 $\mu\text{l}/\text{ml}$, a 58.8 percent reduction (FIG. 5). There was a high correlation between loss of hemoglobin and loss of plasma protein ($r = 0.96$).

The net efflux of sodium ion (Na^+) from mucosa to lumen provides a sensitive index of the integrity of the gastric mucosal barrier. 30 minutes after assault with aspirin and before there was any significant loss of hydrogen ion from lumen to mucosa, the Na^+ concentration had already doubled in both the aspirin and the as-

pirin-glucagon series of tests (FIG. 6). The maximum increases in Na^+ concentration occurred during or immediately after assault with aspirin and were four times the values obtained before administration of aspirin. The mean Na^+ concentrations following injections of glucagon were not significantly different from those obtained from aspirin administration alone.

Aspirin administration increased the net potassium ion (K^+) concentration by a factor of 2.3 to 3.5 during the 90 minutes of administration. This increase in net K^+ efflux persisted after withdrawal of aspirin from the test solution and was not significantly altered at any point in the test by administration of glucagon.

The concentrations of calcium ion (Ca^{++}) and magnesium ion (Mg^{++}) were both significantly increased by aspirin administration. As shown by Periods 4-7, the average concentration of Ca^{++} increased by a factor of 5.2 after administration of aspirin. Although the mean values for Ca^{++} were lower in the glucagon-treated series than in that in which aspirin alone was administered, the differences of means were not statistically significant.

The Mg^{++} concentrations was increased by a factor of 3.2 upon administration of aspirin. The mean values for Mg^{++} concentration were slightly lowered by glucagon administration; however, these differences were not statistically significant.

The results presented hereinabove agree with the recognized finding that aspirin in an acidic environment disrupts the integrity of the gastric mucosal barrier. The above results demonstrate that upon disruption of the integrity of the barrier, typical responses were noted, such as increase in the net efflux of sodium and potassium ions, increase in volume of recovered test solution, and loss of H^+ from lumen to mucosa. There was sustained hemorrhage from mucosa to lumen after the assault with aspirin and for as long as the fundic mucosa was irrigated with 0.1 N HCl.

The results further demonstrate that clearance of aminopyrine increased significantly upon exposure of the Heidenhain pouch to aspirin. Theoretically, at least, the increased clearance of the aminopyrine could be due in part to exudation of aminopyrine through injured capillaries. However, the increase in mucosal clearance of aminopyrine was approximately 150 ml. per each 30 minutes (5 ml./min. $\times$ 30 min., FIG. 3), whereas the total loss of plasma to lumen was less than 2 ml. per each 30 minutes (60 $\mu\text{l}/\text{ml} \times 30$ min., FIG. 5). Therefore, the increase in aminopyrine clearance in fact represents a true increase in mucosal blood flow.

The administration of glucagon effected a significant reduction in clearance of aminopyrine (FIG. 3). The reduction in aminopyrine clearance caused by glucagon is indicative of a genuine reduction in mucosal blood flow.

Glucagon therefore significantly counteracted the action of aspirin with respect to mucosal blood flow. As is evident from FIG. 4, glucagon also caused substantial reduction in mucosal hemorrhage. However, this reduction does not appear to be directly dependent upon the reduced mucosal blood flow.

That this is true is evident from a comparison of the aminopyrine clearance (FIG. 3) with the total blood (FIG. 4). The reduction in mucosal blood flow (aminopyrine clearance) due to administration of glucagon was evident from the outset of administration (Period 5) and through Periods 6 and 7. However, its effect had virtually expired by the end of Period 8. In contradistinction, the total blood decreased from the outset of glucagon administration (Period 5), and the reduction continued to be in evidence through to and beyond the end of the test (Period 12). Therefore, the reduced hemorrhaging was distinctively in excess of that which would be attributable to the recognized reduction in mucosal blood flow.

It is apparent from the above, therefore, that glucagon has significant utility in arresting gastric bleeding in subjects experiencing same or in preventing or diminishing gastric bleeding in subjects susceptible thereto, and caused, for example, by ingestion of an ulcerogenic anti-inflammatory agent, particularly aspirin, or by the presence of a gastric ulcer.

I claim:

1. A method for alleviating gastric mucosal bleeding which comprises parenterally administering to a mammal a therapeutically effective amount of glucagon.

2. Method of claim 1, in which the glucagon is administered subcutaneously.

3. Method of claim 1, in which a total of from about 1.0 μg to about 200 μg . of glucagon is administered per kilogram of body weight.

4. Method of claim 3, in which a total of from about 25 μg . to about 150 μg . of glucagon is administered per kilogram of body weight.

5. Method of claim 4, in which a total of from about 25 μg . to about 100 μg . of glucagon is administered per kilogram of body weight.

6. Method of claim 1, in which the total dosage of glucagon is administered in multiple cumulative doses.
